(57) **CLAIM**

The ornamental design for a dehydrator, as shown and described.

DESCRIPTION

FIG. 1 is a front elevational view of a dehydrator showing my new design;

FIG. 2 is a rear elevational view thereof;

FIG. 3 is a left side view thereof;

FIG. 4 is a right side view thereof;

FIG. 5 is a top plan view thereof;

FIG. 6 is a perspective view thereof;

FIG. 7 is a perspective view of the dehydrator, with all components omitted except for the dehydrator basket; the dehydrator basket is shown separately from other components in this view for clearer illustration of its shapes;

FIG. 8 is another perspective view of FIG. 7; and,

FIG. 9 is an exploded view of the dehydrator.

The broken lines illustrate portions of the dehydrator that form no part of the claimed design.
